Primary Examiner — Lucy Lieberman(74) *Attorney, Agent, or Firm* — Krieg DeVault LLP;
Clifford W. Browning(57) **CLAIM**

The ornamental design for a watch case, as shown and described.

DESCRIPTION

FIG. 1 is a top view of the watch case of the present invention.

FIG. 2 is a bottom view of the watch case of FIG. 1.

FIG. 3 is a right side view of the watch case of FIG. 1.

FIG. 4 is a left side view of the watch case of FIG. 1.

FIG. 5 is a front view of the watch case of FIG. 1.

FIG. 6 is a back view of the watch case of FIG. 1; and,
FIG. 7 is a top, right-side perspective view of the watch case of FIG. 1.

The broken lines showing in FIG. 2 are for the purpose of illustrating the bottom of the watch case of the present invention, and form no part of the claimed design.
